UNITED STATES PATENT OFFICE.

CHARLES J. BUCHHEIT, OF BUFFALO, NEW YORK.

DESIGN FOR A SPOON.

SPECIFICATION forming part of Design No. 34,199, dated March 12, 1901.

Application filed February 7, 1901. Serial No. 46,454. Term of patent 3½ years.

To all whom it may concern:

Be it known that I, CHARLES J. BUCHHEIT, a citizen of the United States, residing in Buffalo, in the county of Erie and State of New York, have invented and produced a new and original Design for Spoons, of which the following is a specification, reference being had to the accompanying drawing, forming part thereof.

10 The figure in the accompanying drawing shows a front elevation of my new design. The leading features of my new design consist of a miniature pan forming the bowl of the spoon and a spoon-handle proper provided

15 at its lower end with a hand which grasps or holds the handle of the miniature pan.

As shown on the drawing, A represents the handle of the spoon, which terminates at its lower end in a hand a.

B represents a miniature pan provided with 20 an upwardly-projecting handle b, which latter is held or grasped by the hand a, thus forming a continuation of the handle A.

Having thus described my invention, what I claim as new, and desire to secure by Letters 25 Patent, is—

The design for a spoon, substantially as herein shown and described.

CHARLES J. BUCHHEIT.
